RAM GUIDE FOR LIFT TRUCK

George F. Quayle, Philadelphia, Pa., assignor to The Yale & Towne Manufacturing Company, Stamford, Conn., a corporation of Connecticut

Application August 31, 1953, Serial No. 377,604

3 Claims. (Cl. 187—9)

This invention relates to industrial trucks of that class in which a hydraulic ram is used to move a load relatively to uprights carried by the truck. More particularly, the invention relates to that type of truck in which the uprights are adapted to carry a secondary pair of uprights for movement relatively to the first or primary uprights, a load-lifting carriage being then mounted for movement on the secondary uprights. The hydraulic ram lifts the carriage through chains secured at one end to the carriage and at the other end relatively to the primary uprights of the truck. The ram is adapted to lift the secondary uprights through physical engagement therewith after the carriage has been moved a relatively short distance on the secondary uprights, so that thereafter the ram lifts both the secondary uprights and the carriage.

In an arrangement of the particular class, it will be appreciated that very considerable stresses are transmitted to the hydraulic ram by any force tending to move the piston of the ram laterally in any direction relatively to the cylinder of the ram. In other words, it is extremely important that the forces acting on the piston be transmitted along the center line of the piston and the cylinder of the ram.

It is the purpose of my invention to contribute means whereby all pressures applied to the piston will be axial thereof, in all positions of the secondary uprights relatively to the ram.

To understand fully the problem solved by my invention, it must be considered that the ram in trucks of this class is mounted relatively to the primary uprights, but that the secondary uprights do not always remain perfectly aligned with the primary uprights. Particularly as the secondary uprights are extended upwardly, these uprights lean somewhat under the weight of the load, and may also tend to cock in a lateral direction relatively to the primary uprights. Because the movement of the load carriage is parallel to the secondary uprights, this movement is at an angle to the primary uprights when the secondary uprights lean or cock, and the chains through which the carriage is lifted then exert a pull that is out of alignment with the primary uprights. By my invention, I cause the forces that lift the carriage to be applied in the axis of the ram without regard to the leaning of the secondary uprights or to the particular direction of the pull exerted by the lifting chains.

As a particular feature of my invention, I guide the ram piston always relatively to a particular point at the upper end of the secondary uprights, with the ram cylinder moving transversely to maintain the longitudinal axis of the ram in alignment with this point as the secondary uprights lean or cock relatively to the primary uprights. Thereby the ram is substantially aligned with the secondary uprights at all times, and when the lifting chains are out of alignment with the primary uprights, the stresses transmitted by these chains to the ram are in the axis of the ram. As a further part of this feature, I arrange the ram piston to enter into lifting engagement with the secondary uprights coaxially with the aforesaid point relatively to the upper end of these uprights. By this arrangement I enable the ram to lift the secondary uprights through forces that are maintained in the axis of the ram.

2

In order to appreciate further the considerable value

5 of my invention, it should be realized that frequently the secondary uprights in trucks of the particular class will not move downwardly freely when the ram is contracted incidental to the lowering of the carriage. This means that there is a tendency for the piston of the ram to move 10 a considerable distance downwardly from the secondary uprights should these secondary uprights remain in an upward position as the piston moves downwardly with the carriage. To obviate the damage that can result by the eventual freeing of the uprights for movement downwardly against the piston, a lost motion connection is applied between the secondary uprights and the piston to limit the free movement between the two. Should the uprights be prevented by some obstacle from moving downwardly, very considerable pressure can be developed 15 between the piston and the secondary uprights through this lost motion connection because of the heavy load that is imposed on the piston by the carriage and the chains during the lowering of the loaded carriage. It is a feature of my invention that the lost motion connection is applied axially of the piston so that no side thrusts 20 are applied between the piston and the cylinder because of the operation of the lost motion connection.

As a detailed feature of my invention, I utilize a guide rod for guiding the ram piston relatively to the secondary

30 uprights with this rod acting also as a lost motion connection between the piston and these uprights. I maintain the rod in axial alignment with the ram at all times, and for this purpose I mount the rod in the piston through bearing means that are spaced a considerable distance 35 along the length of the rod. More particularly, I prefer to utilize bearing means for the rod in the upper end of the piston, and also lower bearing means through which the lower end of the rod is held in an axial position in the piston. I attach the upper end of the guide rod to the

40 secondary uprights in such a way that the rod is extended when the piston moves downwardly relatively to these uprights, but I limit the extension of the rod by providing on the rod a collar that is adapted to engage the upper end of the piston. By so limiting the extension of the rod, I maintain the lower bearing means always a considerable distance below the upper bearing means, and I can thereby hold the rod very effectively in axial relation to the piston. Because the ram then acts always in alignment with the point at which the guide rod is attached to the secondary uprights, the leaning or cocking of these uprights does not cause lateral stresses in the ram. It is, of course, the collar on the guide rod that enables me to utilize the ram piston to move the secondary uprights downwardly.

55 While I shall describe my invention without regard to pivoting uprights, it should be understood that my concept will operate in substantially the same fashion whether or not the primary uprights are pivoted on the main frame of the truck or are rigidly secured thereto.

I have thus outlined rather broadly the more important features of my invention in order that the detailed description thereof that follows may be better understood, and in order that my contribution to the art may be better appreciated. There are, of course, additional features of 60 my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart

from the spirit and scope of my invention, in order to prevent the appropriation of my invention by those skilled in the art.

Referring now to the drawings:

Fig. 1 is a side view showing my novel ram guide embodied in a lift truck.

Fig. 2 is a plan view taken on the line 2—2 of Fig. 1.

Fig. 3 is a partial view taken on the line 3—3 of Fig. 2, with parts broken away to show the ram guide.

Fig. 4 is a longitudinal section showing details of the ram guide, with the ram piston extended to lift the secondary uprights.

Fig. 5 is similar to Fig. 4, but with the ram guide limiting downward movement of the piston relatively to the secondary uprights.

Fig. 6 is a view taken on the line 6—6 of Fig. 1, showing the mounting of the ram cylinder.

In order that my invention may be fully appreciated, I show in Fig. 1 of the drawings an industrial lift truck T of the class having a pair of primary uprights 10, a pair of secondary uprights 11, and a load carriage 12 upon which are lifting forks 13. As may be best seen in Fig. 2, the uprights 10, 11 are formed as channel members, with rollers 14 engaged in the channels of the primary uprights 10 to guide the secondary uprights 11 for vertical movement, and rollers 15 similarly guiding the carriage 12 for vertical movement on the secondary uprights 11. The primary uprights 10 are integrally connected as a unit by upper cross member 16 shown best in Figs. 1—3, lower cross member 17 shown best in Figs. 1 and 6, and an intermediate cross member 18 also shown best in Figs. 1 and 6.

I show in Figs. 1, 2, and 3 a pair of rollers 19 on the upper cross member 16 for guiding the secondary uprights 11 in a lateral sense relatively to the primary uprights 10. A pair of rollers 20 serve a similar purpose at the lower ends of the uprights 11, as shown in Figs. 2 and 6. Also, the carriage 12 has rollers 21, Fig. 2, for guiding it laterally relatively to the secondary uprights 11.

The lower cross member 17 has upon it a hydraulic ram, indicated generally by the numeral 22, for lifting both the load carriage 12 and secondary uprights 11. Ram 22 has a cylinder 23 mounted relatively to the primary uprights 10 through the lower cross member 17 in position between the secondary uprights 11. In the cylinder 23 is a piston 24 adapted to be extended upwardly by fluid pressure, with a packing 25, shown in Figs. 3 and 4, applied between the piston and cylinder to prevent leakage of fluid. In the construction that I have chosen to illustrate, the packing 25 is retained in position between rings 25a, 25b, and the packing 25 together with the rings would of course accept considerable stress in the event that side thrust were to occur between the piston and cylinder.

On the upper end of the piston 24 is a cross head 26 having a pair of wheels 27 over which lifting chains 28 are reeved, as seen in Figs. 1 and 3. I show the chains 28 secured at one end to the ram cylinder 23 through a bracket 29, and at the other end to the load carriage 12 through attachment members 30, shown in Fig. 6. The ram piston 24 when first extended from its positions of Figs. 1 and 5 to its position of Fig. 4 lifts the carriage 12 through the chains 28. With the cross head 26 engaging an upper cross member 31 on the secondary uprights 11, as shown in Fig. 4, further extension of the ram piston 24 moves the secondary uprights 11 upwardly as the carriage 12 continues its lifting movement. The carriage 12 moves at double the speed of the secondary uprights 11 because the movement of the ram piston 24 is multiplied by the chain arrangement. When the carriage 12 reaches its limit of upward movement relatively to the secondary uprights 11, the carriage engages the cross member 31 to lift these uprights whereby the carriage can move still further upwardly, with the member 31 then

moving away from the cross head 26. So far as I have described it, this construction is conventional.

I have already described the leaning or cocking action of the secondary uprights in trucks of the particular class. Thus, in the truck that I illustrate, the weight of a load lifted on the forks 13 tends to cause the secondary uprights 11 to lean forwardly relatively to the primary uprights 10. Because of small clearances incidental to the construction of the rollers 14 on the secondary uprights 11, these uprights actually do lean, and the leaning action becomes more pronounced as the secondary uprights 11 are extended upwardly. In a somewhat similar way, the secondary uprights 11 tend to cock in a transverse direction when the forks 13 support a load that is offset relatively to the center line of the truck. Since the load carriage 12 is mounted on the secondary uprights 11, these uprights when in cocked or leaning position cause the load lifting chains 28 to exert a pull that is out of alignment with the primary uprights 10.

20 I shall now describe in detail the exceedingly novel construction whereby I maintain the pull of the lifting chains in alignment with the hydraulic ram, and so control the forces on the ram as to act in the axis of the ram when the secondary uprights lean or cock.

25 Thus, I mount the ram 22 for limited universal movement relatively to the primary uprights 10, utilizing preferably for this purpose a tubular member 32 on the cross member 17, as well shown in Figure 6. Somewhat above the lower end of the ram cylinder 23 is a flange 33 supporting the cylinder on the upper end of the tubular member 32. The lower end 34 of the cylinder is then positioned within the tubular member 32 to hold the ram 22 in position on the cross member 17. The lower end of the ram has a lateral clearance relatively to the 30 member 32, whereby the ram 22 can lean relatively to the primary uprights 10.

35 At the upper end of the ram piston 24 I provide a novel guide rod 35, best seen in Figures 3, 4, and 5. I form the upper end of the piston 24 preferably as a screw plug 36, and this plug has a central opening 37 in which the guide rod 35 is adapted to slide in the axis of the piston 24. Packings 38 prevent the leakage of fluid from the upper end of the piston 24 around the rod 35. The screw plug 36 has a laterally extending flange 39, and it is through this flange, incidentally, that I mount the cross head 26 on the piston 24.

40 It is extremely important to note that I hold the lower end of the guide rod 35 in the axis of the piston 24, and I show for this purpose a bushing 40 retained on the lower 45 end of the rod by snap rings 41. The bushing 40 is adapted to slide on the inner surface of the piston 24, and is formed to allow the passage of fluid around it so that its movement is not obstructed by fluid in the piston. Further, I mount a collar 42 integrally upon the guide rod 35 at an intermediate point in the length of the rod.

50 By engaging the screw plug 36 in the position shown in Fig. 5, the collar 42 limits outward movement of the rod 35 relatively to the piston 24. Through this arrangement, the screw plug 36 and bushing 40 are maintained always in quite widely separated positions, and are effective therefore as bearing means at two different points along the length of the guide rod 35 to hold the rod aligned in the axis of the ram piston 24.

55 To illustrate the attachment of the upper end of the guide rod 35 at a particular point relatively to the upper end of the secondary uprights 11, I show in Figs. 4 and 5 a reduced upper end portion 43 on the guide rod 35 positioned in an opening in the cross member 31, and retained in this opening by a snap ring 44. It will be 60 apparent that the rod 35 guides the piston 24 relatively to the point at which the rod is attached to the cross member 31. When the secondary uprights 11 lean, therefore, the ram 22 also leans by movement of the lower end 34 of the ram cylinder 23 in the tubular 65 mounting member 32. Because the guide rod 35 is held

actually in the axis of the ram piston 24, the forces applied to the ram 22 by the lifting chains 28 are maintained in alignment with the ram. Also, the piston 24 when engaging the cross member 31 as shown in Fig. 4, lifts the secondary uprights 11 through forces applied in the axis of the ram.

It will be observed further that the collar 42 on the guide rod 35 enables me to utilize the rod as a lost motion connection for limiting downward movement of the ram piston 24 relatively to the secondary uprights 11. Thus, in the event that the secondary uprights 11 do not move freely downward, the downward movement of the piston will cause the screw plug 36 to engage the collar 42 as in Fig. 5, and the pull of the lifting chains 28 can then act through the piston 24 and rod 35 to pull the secondary uprights 11 downwardly. In this instance, as during the lifting action of the ram, the forces applied to the ram are aligned with the ram axis without regard to the leaning or cocking of the secondary uprights.

Through the novel construction that I have conceived, I enable the lift ram in a truck of the particular class to act without side thrust between the ram piston and cylinder, and I thereby enable the ram to operate efficiently and without the damaging effects that are a result of side thrust.

I believe that the construction and operation of my novel ram guide will now be clearly understood, and that its very considerable merit will be fully appreciated by those skilled in the art.

I now claim:

1. In a truck of the class described, a main frame having a pair of spaced uprights, a member mounted for vertical lifting and lowering movement on said uprights, a hydraulic ram including a cylinder and a piston in said cylinder for moving said member on said uprights, mounting means for said ram cylinder positioned between said uprights and fixed relatively thereto, said mounting means being formed to support said ram cylinder for limited universal movement whereby said ram cylinder may be maintained in predetermined alignment relatively to said member, a guide rod for said ram piston and cylinder mounted at its upper end on said member and carrying at its lower end within said ram piston a bushing coacting with the inner surface of said ram piston, and bearing means in which said guide rod slides mounted on said ram piston, the said bearing means and the bushing causing said guide rod to have contact with said ram piston at two linearly spaced surfaces whereby said guide rod is held in alignment with the axis of said ram piston for moving said ram piston and cylinder relatively to said mounting means.

2. In a truck of the class described, a main frame having a pair of spaced uprights, a member mounted for ver-

tical lifting and lowering movement on said uprights, a hydraulic ram including a cylinder and a piston in said cylinder for moving said member on said uprights, mounting means for said ram cylinder positioned between said uprights and fixed relatively thereto, said mounting means being formed to support said ram cylinder for limited universal movement whereby said ram cylinder may be maintained in predetermined alignment relatively to said member, a guide rod for said ram piston and cylinder mounted at its upper end on said member and extending downwardly into said ram piston, said guide rod carrying at its lower end within said ram piston bearing means coacting with the inner surface of said ram piston, and additional bearing means between said guide rod and piston linearly displaced from said first bearing means for guiding said guide rod relatively to said piston, the said two bearing means causing said guide rod to have guiding contact with said ram piston at two linearly spaced surfaces whereby said guide rod is held in alignment with the axis of said ram piston for moving said ram piston and cylinder relatively to said mounting means.

3. In a truck of the class described, a main frame having a pair of spaced uprights, a member mounted for vertical lifting and lowering movement on said uprights, a hydraulic ram including a cylinder and a piston in said cylinder for moving said member on said uprights, mounting means for said ram cylinder positioned between said uprights and fixed relatively thereto, said mounting means being formed to support said ram cylinder for limited universal movement whereby said ram cylinder may be maintained in predetermined alignment relatively to said member, a guide rod for said ram piston and cylinder mounted at its upper end on said member and carrying at its lower end within said ram piston a bushing coacting with the inner surface of said ram piston, bearing means in which said guide rod slides mounted on said ram piston, the said bearing means and the bushing causing said guide rod to have contact with said ram piston at two linearly spaced surfaces whereby said guide rod is held in alignment with the axis of said ram piston for moving said ram piston and cylinder relatively to said mounting means, and a collar fixed to said guide rod for limiting the outward movement of said guide rod with respect to said ram piston.
